UNITED STATES PATENT OFFICE.

RUDOLPH KOCH, OF TEMPLE, TEXAS.

CHURN.

No. 852,067.

Specification of Letters Patent.

Patented April 30, 1907.

Application filed June 5, 1906. Serial No. 320,320.

To all whom it may concern:

Be it known that I, RUDOLPH KOCH, a citizen of the United States, residing at Temple, in the county of Bell, State of Texas, have invented certain new and useful Improvements in Churns; and I do hereby declare the following to be a full, clear, and exact description of the invention, such as will enable others skilled in the art to which it appertains to

make and use the same.

This invention relates to churns and more particularly to dashers therefor and has for its object to provide a dasher which may be used in connection with any churn of the vertical type and which will be extremely simple and cheap.

Other objects and advantages will be apparent from the following description.

In the drawings forming a portion of this specification and in which like numerals of reference indicate similar parts in the several views, Figure 1 is a side elevation of the present dasher. Fig. 2 is a top plan view. Fig. 3 is a vertical section on line 3—3 of Fig. 2, taken through the angle irons, the shafts being shown in elevation. Fig. 4 is a bottom plan view.

Referring now to the drawings, there is shown a churning top 5 having a central opening 6 therein and having secured thereupon an upwardly extending metallic yoke 7 having an opening 8 in its bight registering with the opening 6. A shaft 9 is revolvably engaged in the openings 6 and 8 and has secured thereupon a bevel gear 10 which rests upon the churn top 5 to hold the shaft against downward movement. Secured upon the top at opposite sides of the yoke 7, there are a pair of upwardly extending angle irons 11 having a horizontal shaft 12 journaled therein and extending above the yoke, and this shaft carries an operating crank 13. A bevel gear 14 is secured upon the shaft 12 and meshes with the gear 10.

Mounted upon the shaft 9 below the top 5 and in close relation thereto, there is a cross

bar 15 which is thus arranged to hold the shaft against upward movement and a cross bar 16 is secured to the lower end of the shaft 9 and extends parallel to the cross bar 15, 50 these cross bars having alining openings 15' and 16' in their ends which receive the trunnions of paddles 17, these paddles having rounded end portions 17' and connecting reduced necks 18. 55

As will be readily understood, the present mechanism may be used in connection with any churn having a top of the size to receive the top 5 and as churns are generally manufactured in standard sizes, the mechanisms 60 may be produced in corresponding sizes to suit different churns.

It will be seen that the shaft 9 is revolved, the contents of the churn coming against the paddles 17 which cause them to revolve, and, 65 as shown, the end portions 17' of the paddles extend slightly further beyond the axes thereof in one direction than in the other so that the paddles are revolved. And when placing the dasher in a churn, the paddles are 70 so disposed that they will be rotated in opposite directions to give an increased agitation to the contents of the churn. The top 5 is of course arranged to fit the churn air tight and the present dasher may be used in connection 75 with a stone jar, as shown in Fig. 5.

What is claimed is:

In a churn dasher, the combination with a shaft, of transversely extending spaced cross bars carried by the shaft, and paddles journaled at their ends in the cross bars, said paddles including rounded end portions and a connecting reduced neck, said end portions extending further in one direction beyond the axes of the paddles than in the other. 85

In testimony whereof, I affix my signature, in presence of two witnesses.

RUDOLPH KOCH.

Witnesses:

M. A. GIBSON,
E. F. GIBSON.
